John Lammom

The Schedule referred to in these Letters Patent and making part of the same, containing a description in the words of the said John Lammom himself, of his "Improvement in the Threshing Machine & Horse Power."

This invention is adapted to the threshing of Wheat, Rye, Oats &c. The threshing Machine consists in its general construction of a horizontal cylinder, resting in a frame about three feet and six inches in height and about three and a half feet square, suspended the cylinder and nearly in contact with it, is placed a bar piece of the same length of the cylinder and about twelve inches in width, the upper side being concave to correspond with the circle of the cylinder. The cylinder is supplied with three spiral rows of short metal teeth extending the whole length of the cylinder and in rows about half an inch apart, and the bar piece with eight rows of similar teeth, between which, those of the cylinder pass when the machine is in operation. A horizontal covering extends over the cylinder and top of the frame and serves to bind the frame together. On one side of the cylinder a board or front piece extends from the covering downwards nearly to the center of the cylinder. At that point is connected with the frame an apron the width of the frame and about three feet in length placed on an angle of about forty five degrees descending towards the machine. At the termination of the apron on the machine an aperture is formed between it and the front piece, through which the material to be threshed passes from the apron to the cylinder. The cylinder is put in a quick motion by horse or other power, and the grain being spread out upon the apron and brought in contact with the cylinder by its motion is drawn through between the teeth of the cylinder and those of the bar piece, and by this operation the grain is separated from the straw. The improvement in the threshing machine hereby intended to be patented and secured, consists in the

Drawing

form of the teeth of the cylinder and be spined, and an alternating up and down position of the teeth by moving the bed piece or cylinder. — The teeth should be about three eighths of an inch in diameter, and project about three fourths of an inch from the surface of the cylinder and bed piece, and be of a size to be furnished to support the outer end, and terminate in a point. The bed piece is so placed in the frame as by its elevation or depression the teeth of the bed piece and cylinder are separated or brought nearly in contact, so as to be adapted to the different kinds and situations of the game intended to be tracked. The same end may be attained by the elevation and depression of the cylinder. — The horse power consists of a horizontal wheel of about twenty four feet in diameter with a perpendicular shaft about sixteen inches in diameter, and about eight feet in height, and a turning upon an axis in a bed piece on the ground or other, and the other in a permanently secured base or frame. The wheel is placed near the upper end of the shaft, and consisting of a strop, cord or chain, pulled round the periphery of the wheel, and around a wheel of about twelve in diameter, and a perpendicular shaft about six feet in length. The wheel being placed near the lower end of the shaft and at the upper end of the base and connecting them with a horizontal wheel about four feet in diameter and which passes a similar band to a wheel on the cylinder of the tracking machine, of about three inches in diameter, near the periphery of the large wheel above mentioned and places two perpendicular rollers about six inches apart between which the base of the main wheel is made to pass on its way to the wheel with which that band is connected. — Near the periphery of the four foot wheel is also placed two similar perpendicular rollers about three inches in diameter to pass near the base of that wheel in its passing to the column or base of the cylinder. The base on the four foot wheel passes to the wheel with which it is connected with a band, and passing over to be caught about the perpendicular position of the column, in this a four foot band above

mentioned having at its end the whor or wheel as above described, may be placed in a horizontal position, and in this case the turn of the hand above mentioned is dispensed with, and a similar spring is made in the hand from the large wheel. The whor on the six foot wheel above mentioned may be placed at any convenient distance from the large wheel, as likewise may be the whor on the cylinder of the trilling machine from the four foot wheel, and the whole when thus arranged is propelled by horses attached to cross beams passing through the shaft of the main wheel. The dimensions, proportions and sizes of the different parts of the machinery above described, may be varied as convenience may require, or according to the fancy of the builder, and the materials may be of either wood, iron, or other metal, as may be deemed most expedient, and the above construction of wheels, and beams, may be adapted to any machine, whether driven by hand, horse power, water, or steam.
